UNITED STATES PATENT OFFICE.

WILLIS W. CASE, JR., OF DENVER, COLORADO:

FURNACE.

1,076,346.

Specification of Letters Patent.

Patented Oct. 21, 1913.

Application filed April 15, 1913. Serial No. 761,283.

To all whom it may concern:

Be it known that I, WILLIS W. CASE, Jr., a citizen of the United States, residing in the city and county of Denver, State of Colorado, have invented certain new and useful Improvements in Furnaces; and I do hereby declare the following to be a full, clear, and exact description of the invention, such as will enable others skilled in the art 10 to which it appertains to make and use the same.

This invention relates to improvements in furnaces, and more particularly to furnaces of the muffle type, although some of its features 15 may be advantageously used in connection with crucible assay furnaces.

One of the objects of the invention is to provide a furnace that operates in the manner of a clean coke fire, whereby the entire 20 outer surface of the muffle is uniformly heated, providing an even temperature throughout the interior of the muffle, enabling one to "feather" cupels and secure the desired uniform results.

Another object of the invention is to so support the muffle in association with a system of replaceable supports comprising a 25 heat distributing or radiating medium, that an intense heat may be attained with a comparatively small consumption of fuel.

Another feature of the invention is the damper arrangement, whereby a perfect oxidizing draft of any degree may be attained for cupellation or scorification, or the 30 damper arrangement may be completely closed when it is desired to raise the temperature more quickly, such arrangement enabling all parts of the muffle being supplied with air, so that perfect oxidation may be 35 secured while cupellation is rapid and complete.

Another important feature resides in the provision of an auxiliary flue or by-passage at the front of the furnace, whereby noxious 40 fumes from the muffle may be carried off to outside atmosphere, irrespective of the operation of the damper arrangement, and this feature is very important as the fumes, especially lead, are not only disagreeable to the operative, but are deadly poisonous. 45 And still another important feature is to provide a series of two or more furnaces arranged side by side as a combined unit, incased in a single casing, and being fed fuel 50 and air through a system of branch pipes.

from a single oil reservoir and a single fan blower.

With these and other objects in view, the invention consists of the novel features of construction and in the combination and arrangement of parts, as will be more fully described in the following specification and succinctly pointed out in the appended claims.

For the purpose of more clearly understanding the invention, reference is had to the accompanying drawings, illustrating a practical embodiment of same, in which drawings like characters designate the same parts in the several views, and in which,

Figure 1 is a view in front elevation of a two-muffle furnace of my improved type; Fig. 2 is a top plan view of same, with a portion of the front shelf and oil reservoir broken away; Fig. 3 is a vertical cross-sectional view taken along the plane of the line 3-3 of Figs. 1, 2 and 4; Fig. 4 is a view in longitudinal section taken along the plane of the line 4-4 of Fig. 3; Fig. 5 is a fragmentary transverse sectional view taken on the line 5-5 of Fig. 3. Fig. 6 is a detail view of one form of replaceable heat distributors and supports for the muffle; Fig. 7 is a similar view of another form; Fig. 8 is a similar view of still another form; Fig. 9 is a similar view of a heat distributor and support of triangular cross section.

While many of the features of the present invention may be applied to furnaces of a single, double or triple type, for the purpose 90 of simplicity of illustration, I have simply shown a tandem or two-muffle furnace, and in the description I only refer generally to one section of the sectional two-muffle furnace. Each section is built up of a top and 95 bottom member 1 and 2, made of the best fire clay and forming the lining of the muffle chamber 3, the whole furnace, whether of the single or double type, being incased in a substantial iron jacket or sheathing, 100 with a cast-iron front and back 4 and 5, the side walls of the sheathing being designated by the numeral 6, and the top by the numeral 7. The front 4 is provided with an opening 8 registering with the mouth 9 of the muffle 105 chamber, formed in the fire clay sections, and 10 designates a shelf mounted below said opening 8.

The upper fire clay block 1 and the top 110 sheathing 7 are apertured to form exits for

the products of combustion from the muffle chamber and the air and gases from the interior of the muffle, and this may be in the form of a single large opening communicating with the interior of the muffle chamber at its rear and adapted also to receive the short tubular projection 11 at the rear or closed end of the muffle 12. In the drawings, however, there are shown two openings 13 and 14, the former being disposed at the forward end of muffle chamber and the latter at the rear, the opening 13 being more particularly adapted as a flue to carry off the products of combustion, after complete circulation around the muffle, and the opening 14 providing a ready means of exit for the fumes from the muffle, especially at the rear thereof.

The top surface of the fire clay block 1 is recessed, as at 15 and 16, forming guide ways for housing sliding dampers 17 controlled by handles 18 projecting through slots 19, formed in the top sheathing 7, and operating to damper the muffle chamber flue 13 and the muffle flue 14.

The openings 20 and 21 in the top sheathing 7, forming a continuation of the muffle flues 13 and 14, are flanged to provide a spacing rim, and are slotted as at 22 to communicate with a longitudinal recess 23, extending above the top fire clay blocks 1, at right angles to and immediately above the damper recesses 15 and 16, and this recess 23 forms a continuation of a vertical recess 24 cut in the front surface of the upper fire clay block 1, and forming with the top sheathing 7 and the front 4 of the casing a by-passage from the muffle chamber mouth 9 to the muffle chamber flue or muffle flue, or both of them, as will hereinafter more fully appear.

The walls of the muffle chamber may be provided with ribs 25 guiding the heat currents, and, while this may apply to the side walls also, in the drawings, the rear wall only is shown as being provided with vertical ribs 25 (see Figs. 3 and 5), between which are formed the guiding channels 26 for guiding the heat currents, the ribs also 50 acting as heaters for the vertical walls of the muffle.

The muffle is supported in the furnace by a system of replaceable heat distributing supports. The center supports are preferably of the form shown in Fig. 7, and consist of a plurality of integrally formed superposed rectangular portions 26, diminishing in size and forming a stepped pyramid, having the heat radiating corner and top 60 edges 27 and 28, which also aid in splitting up and deflecting the flame and products of combustion, distributing the heat more evenly below the muffle, the upper step of the pedestal also acting as a heater in direct 65 contact with the bottom of the muffle. As

indicated in Figs. 2 and 9, the central pedestal supports may be formed of triangular cross section, and they are so arranged in the lower compartment of the muffle chamber that they are disposed diagonally with reference to the flame, so that the path of the flame is divided and deflected by the corner edges 27 and pass in a diverging fashion alongside the side surfaces 29 of the steps 26, causing them to throw upwardly an evenly distributed radiation of intensified heat, said pedestals being formed of fire clay or other highly refractory material. One of these pedestals is preferably arranged adjacent the flame entrance 30, and the others are arranged in offset positions, the flame entering the furnace substantially in line with said pedestals, the lower part of the muffle chamber serving as a combustion chamber. The combustion chamber is partly decreased in volume by side tiling 31 on which are supported another series of heater supports of somewhat different form. As shown more clearly in Fig. 6, these side supports are of sectional construction, and consist of a flat base 32 having a vertical side wall 33 that merges into spaced heater lugs or projections 34 forming spaces 35 therebetween to allow of the passage of the heated gases around the sides of the muffle, as will be hereinafter mentioned. Each of these side supports is provided on its ends with shoulders 36 of a height substantially equal to the height of the side walls 33, so that, when two sections are placed end to end, the spacing shoulders 36 form a space between the end heater projections 34 corresponding with the spaces 35 between the heater projection 34 of each unit.

In assembling the side supports it will be noted that I arrange a double row of sections, with their inside edges placed together, as shown in Fig. 4, and these rest on the tiling 31 and are slightly spaced from the side walls of the muffle.

35 designates, conventionally, an oil burner discharging its flame through the opening 30 in the combustion chamber of the furnace.

In Figs. 1 and 2, I have shown two burners, one in each muffle chamber. These 115 burners are fed with fuel oil from a reservoir 36 through a main line pipe 37 and branch pipes 38. Similarly, air is delivered to each burner through the branch pipes 39 connected with a suitable fan blower. The 120 fan blower 40, illustrated in the drawings, is shown as comprising a self-contained electric fan blower directly connected with an electric motor 41, but it is evident that the fan blower, instead of being directly connected with the motor, may be operated by a belt or chain drive. The burners in themselves, forming no specific part of the present invention, are simply referred to as oil burners, and it will be understood that they 130

are provided with proper controlling means for the delivery of the commingled air and oil into combustible relation, and it is also obvious that other types of burners and fuel 5 may be employed.

In operation, it will be seen that the blast of the flame through the burner opening 30 initially impinges against the corner edges 27 of the center support immediately ad-

10 jacent the burner opening which splits up the flame and diverts its passage along the side walls of the sections 26, as before explained, and the heated gases, being thoroughly radiated beneath the muffle, pass 15 through the openings 35 of the double row of heater projections on each side of the furnace and thence upwardly and around the muffle, discharging through the muffle chamber flue 13. Similarly, the air and 20 gases within the muffle pass out through the flue 14, both the muffle flue and the muffle chamber flue being controlled by the dampers heretofore mentioned. When the muffle flue is closed, or nearly closed, and with 25 the opening 8 closed by the usual replaceable door of fire clay, any noxious gases or fumes that are formed in the muffle are carried out through the opening 9 up the by-passages 24 into the horizontal passage 23, thence 30 through the opening or slot 22 in the flanged top sheathing and pass into the flues 13 and 14 above the dampers 17, and thence upwardly through any suitable chimney arrangement to the outside atmosphere.

35 From the foregoing description, the construction and operation of my improved furnace will be clearly understood, but it is obvious that minor changes might be made without departing from the spirit of the 40 invention and without sacrificing any of the vital principles thereof, and the invention is not limited, therefore, to the precise details as shown and described. For instance, in some cases, the hollow truncated conical 45 pedestal support 26^a, shown in Fig. 8, might replace the particular construction of pedestal support shown in Fig. 7, or might be used in connection with them.

In Figs. 2 and 9 I have illustrated the 50 refractory pedestals comprising stepped pyramids 26^b of triangular cross section.

I claim:—

1. In a furnace, the combination of a muffle chamber; heating means therefor; a 55 muffle having a mouth and a discharge outlet; outlet means leading from said muffle chamber for carrying off the products of combustion from said muffle chamber and the heated air and gases from said muffle 60 outlet; dampering means for said muffle chamber outlet; and an auxiliary passage leading from the mouth of said muffle chamber to said muffle chamber outlet, substantially as described.

65 2. In a furnace, the combination of a muf-

fle chamber; heating means therefor; a muffle having a mouth and a discharge outlet; a muffle flue extending through the top wall of said furnace in alinement with said muffle outlet for carrying off the heated air 70 and gases from said muffle; a muffle chamber flue extending through the wall of the furnace; and dampers in said flues, substantially as described.

3. In a furnace, the combination of a muffle chamber; heating means therefor; a muffle having a mouth and a discharge outlet; a muffle flue extending through the furnace wall and adapted to receive the discharge from said muffle outlet; a muffle chamber 80 flue; dampers for said flues; and a by-passage leading from the mouth of said muffle and discharging into one of said flues above its damper, substantially as described.

4. In a furnace, the combination of a muffle chamber; a muffle having a mouth and a discharge outlet; outlet means extending through the wall of said furnace for carrying off the products of combustion from said muffle chamber and the discharge from said 90 muffle outlet, the front and top outer surfaces of the furnace wall being provided with a recess extending from the mouth of the muffle chamber to said outlet means; a damper for said outlet means mounted below said top recess; and a sheathing for said furnace, the front and top walls of said sheathing forming with said recesses a by-passage leading from the mouth of said muffle chamber to said outlet means therefrom above said damper, substantially as 100 described.

5. In a furnace, the combination of a muffle chamber formed from upper and lower sections of refractory material; heating 105 means therefor; a muffle having a mouth and a discharge outlet; a muffle flue leading through said furnace wall from said muffle outlet; a muffle chamber flue for carrying off the products of combustion; recesses on 110 the outer surface of said furnace wall and extending across the outer ends of said flues; a damper slidingly mounted in each of said recesses; a recess disposed at right angles to said damper recesses, on the outer 115 face of said furnace wall and extending from the mouth of the muffle chamber to one of said flues; and a sheathing for incasing said furnace and coöperating with said latter recesses to form a passageway leading from the mouth of the muffle chamber to one of said flues on the outside of its damper, substantially as described.

6. In a furnace, the combination of a muffle chamber, a flame burner discharge therein, a muffle, and a plurality of stepped pyramids of refractory material supporting said muffle and coöperating to provide upwardly-flaring passages for directing heat 125 against said muffle, said several stepped 130

pyramids being arranged in series with their corner edges spaced along lines inclined to the current of the hot products of said burner for successively deflecting and splitting up such hot products.

7. In a furnace, the combination of a muffle chamber; a flame burner discharging therein; a muffle; and a plurality of pedestals of refractory material for supporting said muffle, said pedestals comprising a series of superposed steps triangular in cross-section, forming flame deflecting and heat radiating surfaces and edges, substantially as described.

15 8. In a furnace, the combination of a muffle chamber having tiling or side ledges extending along the lower sides thereof, forming a longitudinal channel therebetween; a muffle of lesser width and height than said 20 muffle chamber; a plurality of pedestal sup-

ports for said muffle disposed within said longitudinal channel; side supports for said muffle, comprising base portions mounted on said tiling and having upwardly-extending spaced heater portions located substantially 25 in line with the side walls of the muffle, forming passageways for the heat and products of combustion to envelop said muffle, the space below said muffle forming a combustion or flame chamber of restricted volume; a flame opening leading into said flame chamber in line with said pedestal supports; and a flame burner discharging into said flame opening, substantially as described.

30 In testimony whereof, I affix my signature, in presence of two witnesses.
